TOP EDGE PROTECTOR FOR AUTOMOBILE DOORS

Benjamin C. McKee, Memphis, Tenn.

Application June 13, 1955, Serial No. 36,483

Term of patent 3½ years

(Cl. D14—6)

FIG. 1.

FIG. 2.

FIG. 3.

FIG. 4.

FIG. 5.

Fig. 1 is an elevational view in reduced scale illustrating the top edge protector for automobile doors embodying my new design.

Fig. 2 is a top plan view on an enlarged scale of the top edge protector of the present invention.

Fig. 3 is a cross sectional view on the line III-III of Fig. 2.

Fig. 4 is a cross sectional view on the line IV-IV of Fig. 2; and

Fig. 5 is a cross sectional view on the line V-V of Fig. 2.

The fragmentary portion of an automobile disclosed by means of broken lines in Fig. 1 is shown only for purpose of illustration.

I claim:

An ornamental design for a top edge protector for automobile doors, as shown and described.
